UNITED STATES PATENT OFFICE.

JOSEPH GAYNOR, OF JERSEY CITY, NEW JERSEY.

MACHINE FOR SHAPING AND FORMING FABRIC CASES.

Application filed August 15, 1922. Serial No. 582,061.

To all whom it may concern:

Be it known that I, JOSEPH GAYNOR, a citizen of the United States, and a resident of Jersey City, in the county of Hudson and State of New Jersey, have invented a new and Improved Machine for Shaping and Forming Fabric Cases, of which the following is a full, clear, and exact description.

This invention relates to a machine for shaping and forming fabric cases with direct reference to cases which contain musical instruments.

The object of the invention resides in the provision of means whereby the fabric can be smoothly stretched over die members in a simple and efficient manner.

A further object of the invention is the provision of means by which the manipulation of the machine by one operator is rendered exceedingly simple.

A still further object resides in the provision of means whereby various adjustments can be made very easily and quickly during the operation of the machine so that it is at all times entirely under the control of the one operator.

Another object resides in the provision of means whereby the die members can be made sectional and the inside thereof provided with engraved portions which when pressed on to the surface of the article being formed will create impressions of leather grains and other designs on the article and which when the die is opened and the sections are pulled out, can be lifted from the other die member without scratching or otherwise injuring the embossing or engraving.

A further object resides in the provision of means whereby with the use of the sectional die the pressing and drawing of the fabric on the die members is made considerably easier than with solid dies, since the complete process of forming a casing takes only about five or six minutes.

A still further object resides in the particular construction and arrangement of dies and in the character of the materials as hereinafter described and claimed and shown in the accompanying drawings.

In the drawings which illustrate the invention in its preferred form

Figure 1 is a vertical section through the machine;

Figure 2 is a plan view of the machine;

Figure 3 is a transverse vertical section

taken through the machine with the die members in their closed position;

Figure 4 is a longitudinal section through the machine, illustrating the shaping move- 60

ments;

Figure 5 is a detailed view;

Figure 6 is a detailed section through the means for operating the die parts simulta- 65

neously;

Figure 7 is a plan view showing the die members;

Figure 8 is a detailed view;

Figure 9 is a horizontal section through a modified form of the machine; and 70

Figure 10 is a section taken on the line 10-10 of Figure 9.

In the drawings the preferred form of the invention as shown involves a table 11, supported on legs 12. A die member 13, preferably a male member, is fastened to the table 11. A sectional female die member is disposed above the male member 13 and is suitably supported on a frame capable of movement in a vertical direction. This 80 frame is formed, as shown, of a plurality of sections 14 of pipe disposed in any suitable manner. It is understood, of course, that the frame supporting the upper die member may be made of other material and ar- 85

ranged in a different manner. To avoid a multiplicity of numerals we are numbering the frame 14 and this number is supposed to represent any one of the pipe sections of the frame forming the upper die member. 90

At its outer edges the frame is provided with castings 15 having bores therein

through which standards 16 extend. These

standards are fastened to the floor at one

end and to, preferably, a channel plate 17 95

in their upper end. This channel plate 17

is provided with a screw feeding device re- 100

presented by the numeral 18, the lower end

of which is connected by a universal joint 19

to a pressure plate 20. This pressure plate 100

bears against the upper end of certain of

the frame sections 14 to connect directly to

the upper portion or cover 21 of the female

die member which is formed of a plurality

of sections. The female die member further 105

comprises movable end sections 22 and 23

and movable side sections 24 and 25, as noted

particularly in Figure 7. The abutting

edges of adjacent sections of this die mem- 110

ber, as shown in Figure 7, are provided with inclined edges, represented by the numeral

26, forming somewhat of a tapered joint.

This tapered joint, it will be observed, permits the sections of the die member to be removed inwardly and outwardly with respect to each other and yet to maintain a 5 rather close edged connection so that in fitting the fabric over the male member the formation of wrinkles or uneven portions is effectively prevented. To the outer faces of these die sections 22, 23, 24 and 25 there are 10 fastened supporting members or castings 27 which in turn are connected to certain sections 14 of the frame. These sections in turn are connected respectively, to castings 28, of which there are a plurality disposed 15 around the die member. These castings are provided with bores through which shafts 29, 30, 31 and 32 extend. The ends of these shafts are connected by sets of bevel gears, represented by the numerals 33 20 and 34, in pairs so that the movement of one shaft is transmitted to the other simultaneously. A handle 35 is connected to the end of one of these shafts and the movement of this handle will cause the movement of each of 25 the other shafts simultaneously with the movement of the one to which this handle is connected, as shown particularly in Figure 6. Each of the castings 28 contains a helical gear 36 adapted to mesh with a worm 30 gear 37 on any one of the above-mentioned shafts. The movement of the worm gear will cause the helical gear to rotate, this helical gear being disposed in a chamber 38 formed within the casting and mounted on 35 a squared end 39 of a shaft 40. The shaft 40 is provided with threaded ends 41 and 42 extending into bushings 43 and 44. The bushing 44 is disposed in the casting and the bushing 43 is disposed in the supporting 40 member or casting 27. It will be understood that between each casting 28 and its adjacent supporting member or casting 27 this arrangement of parts is disposed so as to transmit pressure to the casting or supporting member 27 and thence to the section 45 of the female die member to which said supporting member is connected. The casting 28, of course, is supported and connected to the proper sections 14 of the frame. 50 It will be noted that there are two sets of pressure transmitting mechanisms as above described disposed adjacent each of the end and side sections of the female die member. Therefore, the movement of the handle 35 in one direction or the other will cause the advance or retreat of the above-mentioned sections of the female die member simultaneously. The movement of the upper portion 21 of the female die member is effected 60 by the above-mentioned screw feeding mechanism 18. When this screw feeding mechanism is operated the entire frame, formed of the sections 14, is moved either upward or downward, and during the operation the 65 incidental movement of the handle 35 will

cause the expansion and contraction of the side members of the die member.

The lower edge of each of the lateral side members of the female die member is provided with a recess 45, seen particularly in Figure 4, in which a plurality of roller bearings 46 are suitably mounted. There are preferably two sets of these bearings to each of the lateral sections of the die member. Disposed beneath the edges of the lateral sections of the female die member is a plate or frame 47, preferably forming one integral frame, supported on rods 48 throughout its length, these rods having heads 49 thereon and extending into housings or sleeves 50 connected to the table 11. These housings 50 have threaded adjusting plugs 51 at their bottoms and also contain springs 52 which bear at their lower ends against the plugs 51 and at their upper ends against the heads 49 and are arranged to constantly tend to hold the rods 48 upward and consequently to hold the frame or plate 47 against the lower edges of the lateral sections of the female die member. The frame, throughout its length at intervals preferably adjacent the points of the die sections containing the roller bearings above-mentioned, is provided with an opening 53. Adjacent each of these openings is disposed a bracket 54 connected to the frame 47 by means of bolts 55 having springs 56 resiliently connecting the bolts with the brackets. These brackets support two gears 57 carrying a chain 58. One of these gears is also associated with and mounted on the same shaft with a ratchet gear 59. With this ratchet gear a rack 60 is adapted to co-operate to move it in one direction only. This rack bar 60 is pivotally mounted on the table 11 and a spring 61 bears against it to hold it against the ratchet gear 59. It will be understood, therefore, that in association with each set of roller bearings on the die sections there is disposed an endless chain and a means including the rack bar to operate it. Whenever there is relative movement between the plate or frame 47 and the table 11 especially when they approach each other, the rack bar 60, being relatively stationary, will cause movement of the ratchet gear 59 whereby the chain 58 will be moved in one direction. The fabric represented by the numeral 62 is disposed beneath the edge of the lateral sections of the female die member and above the plate or frame 47, which may also be termed a gripper plate or frame. It will, therefore, be noted that when the lateral sections of the die member are moved downwardly toward the table 11 there is a constant travel of the chains in a direction to feed the fabric toward the center of the die sections, and this action constantly taking place as the female member is moved downward over the male member of the die will 120 125 130

prevent the wrinkling of the fabric as it is being stretched over the corners of the male member. It will also be observed that this action is entirely automatic. Of course, the resistance of the bars 48 to the depression of the gripper frame 47 can be adjusted by means of the plug 51 above referred to. In this manner the fabric can be stretched tightly over the male member in a perfectly smooth and even manner, eliminating the necessity for adopting various expedients to overcome the presence of wrinkles.

As shown in Figure 8, I may mount each of the worm gears 37 on its proper shaft by means of a key 63 so that it can slide along said shaft although rotating therewith. I also may provide collars 64 spaced on the shaft beyond the end of the worm gear 37 and dispose springs 65 between the ends of the worm gear and said collars so that the worm gear may move in one direction or another against the resistance of the springs 65. This particular arrangement can be adapted so that in turning the handle 35 the advance of the lateral sections of the die member need not necessarily be absolutely equal because one die section may bear against the fabric stretched over the male member before another section has come fully in contact with the fabric, and this arrangement, therefore, permits the movement of certain sections for a sufficient interval of time after another section has already been moved as far as possible toward the fabric.

It will be noticed from a consideration of Figures 1, 2 and 3, that the cover section 21 of the female die member is provided at each end with crossbars 73. These bars project beyond the edges of the section 21 and receive rollers 74 mounted in brackets 75. These brackets are connected rigidly to the lateral sections of the female die member and by riding on the ends of the bars 73 provide a firm support to maintain these lateral sections at the proper level with respect to the cover section 21.

In the modification shown in Figure 9, the female member is one integral section 66, hollow, and the male member is formed of a plurality of sections similar to the formation of the female member previously described in the preferred form of the invention. In this instance I provide a shaft 67 provided with a suitable differential gearing arrangement represented by the numeral 68 and adapted to actuate rods 69 connected at their outer ends to the inner faces of the lateral sections 70 of the male member. This shaft 67 can be operated by a handle 71 to effect the simultaneous movement of the sections forward or backward. In other respects the operation of the device and the mechanisms are the same as previously described.

In the operation of the device I dispose a

fabric between one of the die members and the gripper plate or frame and then move the die members toward each other so that one will fit accurately within the other. After they have been moved so that the male member projects fully within the female member and during this fitting I manipulate the handle 35, or the handle 71, as the case may be, to exert the proper pressure of the sections on the fabric and against the other die member. During the time that the die members are approaching each other the mechanism, which I called the shaping mechanism, including the chain 58 and correlated parts, is operating to eliminate or prevent the formation of wrinkles at the corners of the case in the fabric. During the time that the fabric is being treated and stretched over the male die member and the proper pressure is gradually being applied, heat is being applied to the die members, preferably through the gas pipe 72, to the outer surface of one of the members. During the process, this heat is continually applied, a single process requiring only from five to six minutes.

What I claim is:

1. A device for forming fabric into cases, including relatively movable die members, means for gripping the fabric, and means actuated by the relative movement to shape the fabric over the corners of the die member over which it is stretched and shaped.

2. A device for forming fabric into cases, including male and female die members relatively movable, means for gripping the fabric, and means associated with the gripping means and one of said members to shape the fabric adjacent the corners of the case as it is being stretched over the other member to prevent the formation of wrinkles and pleats therein.

3. A device for forming fabric into cases, which includes a frame movable vertically and a die member supported on said frame, a table supporting another die member, one of said die members being sectional, and a single means for moving certain of said sections relatively to each other whereby pressure may be exerted on the fabric.

4. A device for forming fabric into cases, which includes a vertically movable frame, a die member supported on said frame having movable lateral and top sections, single means for moving the lateral sections simultaneously and separate means for moving the top section and the frame simultaneously.

5. A device for forming fabric into cases, which includes a vertically movable frame, a die member supported on said frame having movable lateral and top sections, a single means for moving the lateral sections simultaneously, separate means for moving the top section and the frame simultaneously, a table disposed adjacent said frame, another

4
die member fastened onto said table, and fabric gripping means resiliently supported on said table, said gripping means adapted to engage the fabric between itself and the lower edges of the sectional die member supported on the frame.

6. A device for forming fabric into cases, which includes a vertically movable member, a die member supported on said frame having movable lateral and top sections, a single means for moving the lateral sections simultaneously, separate means for moving the top section and the frame simultaneously, a table disposed adjacent said frame, another die member fastened onto said table, fabric gripping means resiliently supported on said table, said gripping means adapted to engage the fabric between itself and the lower edges of the sectional die member supported on the frame, and means mounted on the gripping means and actuated by the relative movement between the die members to shape the fabric adjacent the corners of the movable die member to prevent the formation of wrinkles thereon during the stretching of the fabric over one of said die members.

7. A device for forming fabric into cases, which includes a pair of die members relatively movable, said members adapted to receive a sheet of fabric therebetween to be stretched over one of said members by the movement of the other member over said first member, and means associated with said die members and actuated by the relative movement therebetween to shape the fabric adjacent the corners of the members to prevent the formation of wrinkles in the fabric at these points.

8. A device for forming fabric into cases, which includes a vertically movable female member, a table disposed beneath said member, a fabric gripping frame resiliently supported on said table and engageable with the lower edge of the female member to grip the fabric, and means on said gripping frame actuated by the relative movement between the female member and the table to shape the fabric whereby the formation of wrinkles at the corners of the case is prevented.

9. A device for forming fabric into cases, which includes a movable female die member, a table disposed beneath said die member, a gripping frame supported resiliently on said table, and held resiliently against the lower edge of the female die member, a plurality of fabric engaging means supported on said gripping frame to engage and shape the fabric during the relative movement of the female member with respect to the table, and means mounted on the table and engaging said shaping means to cause their actuation during said relative movement.

10. A device for forming fabric into cases,

which includes a movable die member, a stationary die member over which the movable die member is to be disposed by progressive movement, a table on which the stationary die member is supported, a fabric gripping frame resiliently supported on said table and held in engagement with the lower edge of the movable die member, a plurality of fabric engaging chains mounted on said gripping frame adjacent the corners thereof and the corners of the movable die member, a rack gear associated with each of said chains, a plurality of rack bars mounted on the table and engageable respectively with said ratchet gears whereby the depression of the female member relatively to the table and the stationary die member will cause the movement of the chains to engage the fabric adjacent the corners of the case during its shaping to pull the fabric in a direction away from the corners of the case whereby the formation of wrinkles at these points of the case is prevented.

11. A device for forming and shaping fabric into cases which includes a female die member having a plurality of independent lateral sections, the abutting edges of said sections being tapered or inclined with respect to each other whereby said sections can be relatively moved and yet maintain a smooth inner configuration.

12. A device for forming and shaping fabric into cases, which includes a female die member having a plurality of independent lateral sections, the abutting edges of said sections being tapered or inclined with respect to each other whereby said sections can be relatively moved and yet maintain a smooth inner configuration, and a single means for moving said lateral sections simultaneously.

13. A device for forming fabric into cases, which includes a plurality of sections of a die member, a power shaft adjacent each of said sections, power connections between said shafts and said sections, a worm gear on each of said shafts adjacent said connection, each of said worm gears mounted slidably on said shaft but rotatable therewith, a pair of collars mounted on each shaft beyond the ends of the worm gear, and springs disposed between the ends of the worm gear and said collars whereby the worm gear may slide to some extent longitudinally but will rotate with the shaft.

14. A device for forming fabric into cases, which includes a female die member having a plurality of lateral sections, power shafts adjacent said sections, single means for operating said shafts simultaneously, power connections between said shafts and said sections whereby said sections are moved simultaneously, and flexible means in said power connections whereby certain of said die sections may be moved after the others.

of said sections have been advanced as far as possible.

15. A device for forming fabric into cases, which includes a vertically movable frame, 5 a sectional female member supported thereon, said member having lateral movable sections and a vertically movable top section, and means whereby the lateral sections are movably supported at a given level from 10 said top section.

16. A device for forming fabric into cases, which includes a vertically movable frame, a sectional female member supported thereon, said member having lateral movable sections 15 and a vertically movable top section, means whereby the lateral sections are movably supported at a given level from said top section, and a single means for moving said lateral sections simultaneously.

20. 17. A device for forming fabric into cases, which includes a vertical movable frame, a sectional female member supported thereon, said member having lateral movable sections and a vertical movable top section, 25 means whereby the lateral sections are movably supported at a given level from said top section, a single means for moving said lateral sections simultaneously, and a separate means for moving said frame and said 30 die member independent of the means for moving the lateral sections of said member.

18. A device for forming fabric into cases, which includes a movable die member, a fabric gripping frame disposed against the 35 lower edge thereof, a table on which said frame is supported, a plurality of bars connected to said frame, a plurality of housing sleeves on said table into which said lower ends of said bars extend, heads on said bars 40 within said housings, adjustable plugs in the bottom of said housings, and a spring in each of said housings disposed between said plugs and said heads whereby the pressure exerted through said bars on said gripping frame can be adjusted.

45. 19. A device for forming fabric into cases,

which includes a sectional die member having lateral movable sections and a movable top section, brackets connected to said lateral sections, crossbars mounted on said top section and engaged by said brackets whereby the lateral sections can be moved are supported from said top section at a given level.

20. A device for forming fabric into cases, 55 which includes a table, a supporting frame disposed over said table, a stationary die member on said table, a movable die member on said frame, means for moving the frame and the die member supported thereon vertically whereby it may be moved down to embrace the stationary die member, said movable die member formed of a plurality of sections, and a plurality of feeding means 60 adapted to move said sections of the movable die member during the feeding thereof downward over the fixed die member to shape a sheet of fabric over the fixed die member with any required degree of pressure. 65

21. A device for forming fabric into cases, which includes a table, a supporting frame disposed over said table, a stationary die member on said table, a movable die member on said frame, means for moving the 75 frame and the die member supported thereon vertically whereby it may be moved down to embrace the stationary die member, said movable die member formed of a plurality of sections, a plurality of feeding means 80 adapted to move said sections of the movable die member during the feeding thereof downward over the fixed die member to shape the sheet of fabric over the fixed die member with any required degree of pressure, 85 and fabric shaping means actuated by the relative movement between the die members to engage the fabric adjacent the corners of the die members whereby the formation of wrinkles or folds in the fabric is prevented. 90

JOSEPH GAYNOR.
